UNITED STATES PATENT OFFICE.

ELWIN R. HYDE, OF BRIDGEPORT, CONNECTICUT, ASSIGNOR TO THE BRIDGEPORT SAFETY EMERY WHEEL COMPANY, INCORPORATED, OF BRIDGEPORT, CONNECTICUT, A CORPORATION OF CONNECTICUT.

MACHINE DRIVE.

Application filed December 7, 1922. Serial No. 605,381.

To all whom it may concern:

Be it known that I, ELWIN R. HYDE, a citizen of the United States, residing at Bridgeport, county of Fairfield, State of Connecticut, have invented an Improvement in Machine Drives, of which the following is a specification.

This invention relates to machine drives and particularly to a driving connection between two shafts or spindles which rotate at a fairly high speed.

It is an object of my invention to provide a driving means between such shafts which will not become overheated in operation and in which means is provided for cooling the power transmitting means between the shafts or spindles.

It is a further object of the invention to provide means whereby the driving connection may run in a bath of oil with means for cooling this oil to thus keep the driving connection from becoming overheated.

With the foregoing and other objects in view, I have devised the construction illustrated in the accompanying drawings. Although my drive is of general application it is adapted for running different types of machines, but for the purpose of illustration I have shown it as applied to a buffering lathe, and in the drawings—

Fig. 1 is a front view of a buffering lathe showing my improved drive applied thereto.

Fig. 2 is an end view thereof looking from the left of Fig. 1.

Fig. 3 is a top plan view of the drive with a portion of the upper section of the enclosing casing broken away to more clearly show the construction.

Fig. 4 is a longitudinal section substantially on line 4—4 of Fig. 3, and

Fig. 5 is a transverse section through the casing substantially on line 5—5 of Fig. 4.

With A. C. motors for two or three phase equipment the standard windings for buffering machines are usually for 1800 or 3600 R. P. M. and there is nothing in between. However, in buffering practice the bulk of the buffering spindles are operated at from 2200 to 2800 R. P. M. according to the size of the buff, the general practice being to run a 12" buff at about 2500 R. P. M. and as buffers are accustomed to working on spindles running at this speed it is very difficult to get them to operate with buffs running

at other speeds, therefore, if the motors are directly connected to the buffering spindles these spindles either run too slow or too fast. Therefore, in order to use these motors and secure the proper speed for the spindles it is necessary to provide some form of drive between the motor and buffering spindles which either give a step-up drive when the low speed motor is used, or a step-down drive when the high speed motor is used. For these relatively high speeds various types of driving means may be used, but I have found that the improved silent chain drive running over suitable sprockets on the spindles is most satisfactory, as usually the motor and buffering spindles are fairly close together in ordinary operation. However, under the high operating speed these drives quickly become overheated and I have, therefore, provided means for maintaining them at the proper temperature.

Referring now to the specific application illustrated, 10 represents the base or pedestal upon which the shaft or spindle 11 to be driven is mounted to rotate in suitable bearings 12, and in the present instance this shaft carries suitable buffering wheels 13, although of course other tools may be operated thereby if desired. Extending from the rear of the pedestal is a supporting bracket 14 on which is mounted the electric motor 15 for driving the spindle 11 and this motor rotates the driving shaft or spindle 16. These shafts are substantially parallel and spaced a suitable distance from each other. On the motor spindle 15 is a sprocket 17, and on the driven spindle 11 is a sprocket 18 over which runs a suitable silent chain 19 of the usual construction. As this chain and sprocket drive is of standard construction I have not shown it in detail, but have merely indicated it in outline. The sprockets 17 and 18 are of course given different sizes depending upon the relative speed desired between the two spindles. In the present layout the high speed motor is used so that a step-down drive to the tool spindle is employed and thus the driving sprocket 17 is smaller than the driven sprocket 18.

As this chain is driven at a relatively high speed it soon becomes unduly heated unless some means is provided for maintaining it at the proper temperature. For this purpose I enclose the driving means in a suit-

able casing, preferably comprising an upper section 20 and a lower section 21 secured together by suitable flanges 22 through which pass suitable screws or bolts 23. The lower section 21 is adapted to hold a suitable bath of oil, as indicated at 24, which is of sufficient height to come up about the lower portion of the chain. Even with this oil bath I have found that the high speed tends to cause the drive to become unduly heated and I have, therefore, provided means for cooling the oil and thus the drive. Of course when the drive operates the oil is thrown against the ends of the casing, and in fact there is more or less of a fine spray of oil within the casing as it is thrown out by the chain as it passes over the sprockets. I have, therefore, provided on the outer walls of the casing suitable heat radiating ribs or fins 25 which will conduct heat away from the casing and the oil to the surrounding atmosphere. To supplement the cooling action of these fins I also provide means for circulating through the casing a cooling fluid, such as air, and as the oil within the casing is more or less of a fine spray this circulation of cooling air through the casing provides a very efficient cooling means for the oil and the driving means.

For circulating the cooling air through the casing I have provided on the motor shaft 16 a fan 26 in alignment with a suitable inlet opening 27 in one side of the casing, which opening should preferably be covered with a fine wire mesh screen 28 to keep dirt from passing into the casing with the air. The fan blades are preferably inclined somewhat so as to draw the air through the inlet opening into the casing, and preferably in the upper wall of the casing I provide an outlet opening 29 for this air. This opening is placed somewhat forwardly of the sprocket 18 so that the oil thrown off from the chain passing over this sprocket will not be thrown out this opening. If it is found desirable, however, suitable baffles or screens may be provided in this outlet opening to separate any oil from the air should it be found that oil is being carried out by the air.

To also give a more reliable lubrication for the chain I provide means for collecting oil as it runs down the inner surface of the casing walls, and discharging this oil onto the inner side of the chain such as the upper side of the lower run. This means comprises a trough 30 open at its upper side and resting against the inner wall of the casing and having a portion extending inwardly, as shown at 31, between the upper and lower runs of the chain, and arranged to discharge the oil collected by the trough onto the top of the lower run. Where the shafts pass through the side walls of the casing I prefer to provide a suitable packing

around the same to prevent oil passing out on these shafts. Such a packing is shown in Fig. 3 and comprises preferably an annular groove in the casing to hold a suitable packing 32 embracing the shaft.

It is believed the operation will be apparent from the foregoing description. As the cool air is drawn into the inlet opening 27 by the fan 26 it comes in contact with the finely divided oil thrown out by the driving means and cools the same. The air passes out the outlet 29 and the cooled oil flows to the bottom of the casing to be again picked up by the driving means, or is conducted to the drive by means of the trough 30. As the oil is thrown against the casing part of the heat is conducted therefrom and disseminated by the fins 25. It will thus be seen that I have provided means whereby these short drives may be employed for relatively high speeds without overheating.

Having thus set forth the nature of my invention, what I claim is:

1. In a machine drive, two substantially parallel spaced shafts, sprockets secured to said shafts, a chain drive about said sprockets whereby one shaft may be driven by the other, means for rotating the driving shaft, a casing about the sprockets and chain and adapted to hold an oil bath for a portion of the chain, and means within the casing for circulating a cooling fluid through said casing.
2. In a machine drive, two shafts, a driving connection between said shafts, a casing about said driving means adapted to hold a bath of oil for a portion of the driving means to run in, and means within the casing for circulating a cooling fluid through said casing.
3. In a machine drive, two substantially parallel shafts, sprockets secured to said shafts, a driving chain connecting said sprockets, means for rotating one of said shafts, a casing enclosing the chain and sprockets and adapted to hold a bath of oil for a portion of the chain, and means within the casing for circulating air through the casing to cool the oil and chain.
4. In a machine drive, two shafts, a driving connection between said shafts, a casing enclosing said driving connection and provided with an air inlet opening and an outlet opening, a fan adjacent the inlet opening driven by one of said shafts and arranged to draw air into the casing through said opening, and a bath of oil in said casing about a portion of said driving connection.
5. In a machine drive, two substantially parallel shafts, a driving connection between said shafts comprising sprockets secured to the shafts and a driving chain running on said sprockets, a casing enclosing said driving connection and provided with

- an air inlet opening and an air outlet opening, a fan adjacent said inlet opening driven by one of said shafts and arranged to circulate air through the casing from said inlet opening to the outlet opening, and an oil bath in said casing enclosing a portion of said chain. 5
6. In a machine drive, two substantially parallel shafts, a driving connection between said shafts comprising sprockets secured to the shafts and a driving chain running on said sprockets, a casing enclosing said driving connection and provided with an air inlet opening and an air outlet opening, said 10 casing being adapted to hold an oil bath for a portion of the chain, means for circulating air through the casing from the inlet to the outlet opening, and means arranged to direct oil from the interior walls of the casing 15 to the inside of the chain. 20
7. In a machine drive, two substantially parallel shafts, a driving connection between said shafts comprising sprockets secured to the shafts and a driving chain running on said sprockets, a casing enclosing said driving connection and provided with an air inlet opening and an air outlet opening, said casing being adapted to hold an oil bath for a portion of the chain, a fan adjacent the 25 inlet opening driven by one of said shafts and arranged to circulate air through the casing from said inlet opening to the outlet 30
- opening, and a trough arranged to collect oil running down the inner surface of one of walls of the casing and direct it to the top or inner side of the lower run of the chain. 35
8. In a machine drive, a pair of shafts, a pair of sprockets carried by said shafts, a driving chain on said sprockets, a casing enclosing the sprockets and chain and containing a bath of oil for a portion of the chain to run in, said casing being provided with an air inlet and outlet openings, a fan driven by one of the said shafts for circulating cooling air through said casing from the inlet to the outlet, and heat radiating fins on the exterior of the casing. 40
9. In a machine drive, a pair of shafts, a pair of sprockets carried by said shafts, a driving chain on said sprockets, a casing enclosing the sprockets and chain and containing a bath of oil for a portion of the chain to run in, said casing being provided with air inlet and outlet openings, a fan driven by one of the said shafts for circulating cooling air through said casing from the inlet to the outlet, heat radiating fins on the exterior of the casing, and a trough arranged to collect oil running down the inner surface of the casing and direct it to the top or inner side of the lower run of the chain. 45
